(57) **CLAIM**

The ornamental design for a stepladder, as shown and described.

DESCRIPTION

FIG. 1 is a front perspective view of a stepladder showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an exploded perspective view thereof;

FIG. 9 is a rear view thereof in a collapsed position; and,

FIG. 10 is a front view thereof, in which one of the legs is folded.

The features shown in broken lines in the drawings depict environmental subject matter only and form no part of the claimed design.

1 Claim, 10 Drawing Sheets
